CAN CARRYING CARTON

Russell James Hennessey, St. Paul, Minn., assignor to Waldorf Paper Products Company, Ramsey County, Minn., a corporation of Minnesota

Application February 21, 1956, Serial No. 566,853

6 Claims. (Cl. 220—112)

This invention relates to an improvement in can carriers wherein it is desired to carry a series of cans arranged in two superimposed rows.

Various types of paperboard sleeves have been produced for carrying a series of cans. Certain of these can containing sleeves are designed to carry a single row of cans while others have been designed to support two rows of cans in side by side relation. While these can carriers have been found extremely successful, in some instances the panels of the cartons do not provide all of the advertising space which the producer of the goods desires. The purpose of the present invention resides in the provision of a carrier for containing two rows of cans in superimposed relation, thus providing a carrier having a large side panel which may be used for advertising purposes.

A feature of the present invention resides in the fact that my can carrier is better proportioned to contain cans of certain types. For example, cans which are of relatively large diameter and which are relatively short in height, require a wide low carrier which is not particularly attractive and which does not provide a large display area on the side walls of the carton. By providing two rows of cans in superimposed relation, these previous difficulties can be avoided.

A further feature of the present invention resides in the provision of a carrier including a central partition wall which is interposed between the under surfaces of the upper cans and the upper surfaces of the lower cans. This wall is provided with tabs which fold inwardly to engage into the recessed ends of the cans. In order to properly contain both of the rows of cans, the inwardly folded tabs are centrally divided and one-half of each tab is folded to engage the under surface of an uppermost can and the other tab portion is folded downwardly to engage the upper surface of a lower can. Thus, all of the cans are securely held in the sleeve-like body.

A further feature of the present invention resides in the fact that by supporting the cans in two superimposed rows, a handle may more readily be provided for carrying the cans. Furthermore, as the rows are placed one above the other, the handle serves more effectively and may be carried more readily than a wider sleeve construction.

These and other objects and novel features of the present invention will be more clearly and fully set forth in the following specification and claims.

In the drawings forming a part of the specification: Figure 1 is a perspective view of the can carrier in can containing condition.

Figure 2 is a vertical sectional view through the carrier showing the manner in which the partition wall is connected to the outer wall panels.

Figure 3 is a perspective view of the can carrier in empty condition.

Figure 4 is a longitudinal sectional view through the carrier and showing the arrangement of the cans therein.

2

Figure 5 is a diagrammatic view of the blank from which the can carrier is formed.

The carrier is indicated in general by the letter A and is designed to carry a series of cans which are indicated by the letter B. The cans B are usually of the recessed end type having a cylindrical and circling wall and slightly recessed end structures.

As best indicated in Figure 5 of the drawings, the blank of which the carrier is formed includes a vertical wall panel 10 which is hingedly connected along a fold line 11 to a top panel 12. The top panel 12 is hingedly connected along a fold line 13 to a side wall panel 14. The side wall panel 14 is hingedly connected along a fold line 15 to a bottom wall panel 16. The bottom wall panel 16 is connected along a fold line 17 to a side wall panel 19. The side wall panel 19 is foldably connected along the fold line 20 to a partition wall panel 21. This partition wall panel 21 is hingedly connected along a fold line 22 to a glue flap 23.

20 The top and bottom wall panels 12 and 16, and the partition wall panel 21 are of approximately the same width. The wall panel 19 is approximately one-half the height of the side wall panel 14. The side wall panel 10 is slightly greater than one-half the height of the side wall panel 14 so as to overlap a portion of the side wall panel 13 so that it may be adhered thereto.

A handle is provided which extends across the top panel 12. This handle is indicated in general by the numeral 24. The handle 24 includes a relatively narrow center portion which is defined by spaced cut lines 25 and 26. The ends of the narrow portions of the handle are connected by diverging cut lines 27 and 29 to more widely spaced generally parallel cut lines 30 and 31 respectively. These cut lines 30 and 31 extend across the fold lines 11 and 13 respectively and into the wall panels 10 and 14.

An aperture is formed in each of these side wall panels between the sides of the wider portions of the handles. In the particular form of construction illustrated, a 40 U-shaped cut 32 is provided in the side wall panel 10, the base of this U-shaped cut coinciding with the fold line 11 and the sides of the U-shaped cut, designated by the numeral 33, being parallel and spaced inwardly from the cut 30. Aligned fold lines 34 extend from the cut 30 to the adjacent cut line 33 at the ends thereof, these fold lines 34 being parallel to the fold line 11.

A similar arrangement is provided in the panel 14. A U-shaped cut line 35 is provided in the panel 14, the base of this cut line extending along the fold line 30, and the parallel sides 36 of the U-shaped cut line extending parallel to and inwardly of the cut lines 31. Aligned fold lines 37 connect the ends of the U-shaped cut with the ends of the cut lines 31.

Alternatively, the portion within the U-shaped cut lines 32 and 35 may be cut away. In the form of construction illustrated, the portion of the side walls within the U-shaped cut lines 32 and 35 remains in the plane of the side wall panels 10 and 14. When the narrow portion of the handle 25 is flexed upwardly, the strips between the U-shaped cut lines and the outer cut lines incline upwardly and inwardly. These strips which connect the center portion of the handle to the side walls extend between spaced cans within the carton and the portion outwardly of the U-shaped cut lines straddles the center cans of the series.

A pair of tabs 39 are foldably connected along parallel fold lines 40 to opposite ends of the top panel 12. The fold lines 40 and the length of the tabs 39 are so proportioned as to engage inwardly of the chimies of the outer cans of the series. In the particular arrangement illustrated, these fold lines 40 are spaced somewhat in-

wardly from the sides of the band as is obvious from Figure 5.

The panel 16 which forms the bottom panel of the carrier is likewise provided with a pair of opposed tabs 41, which are foldably connected to the bottom panel 16 along parallel fold lines 42. These tabs are designed to engage inwardly of the chimes of the outermost cans of the lower layer of cans.

The partition panel 21 is also foldably connected along parallel fold lines 43 to tab structures which are similar in outline to the tabs 39 and 41. The tab structures are indicated in general by the numeral 44 and each tab structure includes a cut line 45 which divides the same into a pair of tabs 46 and 47. The tab structures are preferably provided with curved outlines or edges which are designed to follow the contour of the inner side of the chime of a can.

The blank thus formed is folded and glued in the manner best illustrated in Figure 2 of the drawings. The blank is folded along the fold line 17 and the glue flap 23 is adhered to the center portion of the wall panel 14. The blank is next folded along the fold line 13 so that the marginal end of the wall panel 10 overlaps the upper portion of the wall panel 19 and is adhered thereto. The partition panel 21 is then interposed between the top panel 12 and the bottom panel 16 when the carton is opened into the form illustrated in Figure 2 of the drawings.

When the cans B are inserted into the carrier, one series of cans, such as three cans, are inserted between the bottom panel 16 and the partition panel 21 and another series of cans is positioned between the partition panel 21 and the top panel 12. As the cans are inserted, the flaps 39 attached to the top panel 12 are folded inwardly to engage into the recessed ends of the uppermost series of cans. In a similar manner, the tabs 41 are folded inwardly to engage into the recessed ends at the bottom of the lower row of cans. One pair of tabs, such as 46, are folded upwardly to engage into the recessed ends of the lower ends of the uppermost row of cans and the other set of flaps, such as the flaps 47, are folded downwardly and inwardly to engage into the recessed upper ends of the lower row of cans. When thus engaged, all of the cans are held in place.

The handle 24 normally remains in the plane of the panels in which it is formed. However, by engaging the center portion of the handle and pulling the same upwardly, the strap portions extending into the side wall panels 10 and 14 will incline inwardly and upwardly permitting the center portion of the handle to be bowed upwardly a distance sufficient to get at least some of the fingers of the hand beneath this handle. The package may then be conveniently carried.

In accordance with the patent statutes, I have described the principles of construction and operation of my can carrier, and while I have endeavored to set forth the best embodiment thereof, I desire to have it under-

stood that obvious changes may be made within the scope of the following claims without departing from the spirit of my invention.

I claim:

- 5 1. A can carrier including rectangularly arranged side and end walls, and a partition wall secured parallel to two opposed walls and interposed therebetween, flaps hingedly secured to opposite ends of said two opposed walls, and flaps hingedly secured near opposite ends of said partition wall, said last named flaps being split so that one portion of each flap may fold above the partition wall and the other portion of each flap may fold on the opposite side of said partition wall.
- 10 2. A can carrier for carrying cans having recessed ends, the carrier including opposed side walls, and a top wall and a bottom wall connecting said side walls, a partition wall secured intermediate said top and bottom walls and extending parallel thereto, flaps hingedly secured to opposite ends of said top and bottom walls, said flaps being foldable inwardly to engage into the recessed ends of certain of said cans and to resist outward movement of said cans, said partition wall also including flaps foldably connected to opposite ends thereof, said last named flaps being split transversely of the fold line hingedly connecting said flaps to said partition wall, one portion of each flap being foldable upwardly and inwardly to engage the lower ends of cans positioned above said partition wall, and the other portions of said flaps being foldable downwardly and inwardly to engage into the upper ends of certain of said cans positioned between said partition wall and said bottom wall.
- 15 3. The construction described in claim 2 and including a strap handle extending across said top panel, said strap handle extending downwardly into said side wall panels.
- 20 4. The construction described in claim 2 and including a strap handle extending transversely of said top panel, said handle having spaced apart connecting portions connecting opposite ends of said strap handle to said side walls.
- 25 5. The construction described in claim 2 and in which said flap includes an arcuate end.
- 30 6. A can carrier including rectangularly arranged side and end walls, and a partition wall secured parallel to said end walls and interposed therebetween, said walls forming a pair of superimposed open ended sleeves, can retaining means hingedly connected to said end walls near opposite ends thereof, and can retaining means foldably connected to said partition wall and foldable in opposite directions therefrom to be engageable with cans on opposite sides of said partition wall.
